UNITED STATES PATENT OFFICE

2,423,712

INSOLE FOR WELT SHOES

Euclid I. La Chapelle, Brockton, Mass.

Application November 6, 1946, Serial No. 708,008

6 Claims.

(Cl. 36—22)

1

This invention relates to insoles for welt shoes and more particularly to the unchannelled ribbed insole for welt shoes herein shown.

The term "shoe" occurring in the specification and in the claims is to be interpreted to include the term "boot."

My present invention is directly solely to the improvement of the unchannelled ribbed insole for a welt shoe in the form shown in Figs. 3 and 4 in the patent to Eno, No. 1,998,125, April 16, 1935, and for further description the said patent may be referred to.

The said unchannelled ribbed insole for a welt shoe has been for some time and now is in use in some shoe factories manufacturing Goodyear welt shoes giving reasonable wear and selling at reasonable prices i. e. at popular prices, and, insofar as I am aware, of all the insoles for welt shoes in actual use in the making of Goodyear welt shoes, the said insole is the most flexible and is the only unchannelled ribbed insole for a welt shoe which retains the original smoothness of its top side plane face; and which permits of the use of a thinner body insole than any other known insole in use in the making of Goodyear welt shoes, and for that reason and for the further reason that its mode of construction is far less costly than any other known insole for a welt shoe.

But the sewing rib of the said unchannelled ribbed insole however, is in need of reinforcement at its toe part, such as herein proposed, due to the straining action thereupon at the toe lasting machine operation. For instance, whenever a substantial box-toe, of the conventional type embodied in a man's or a boy's Goodyear welt shoe, is provided in a shoe incorporating the said insole, then the toe-wipers of the toe lasting machine in coming in contact with the upper, the said substantial box-toe, and the cemented sewing rib of the said insole, first force the cemented sewing rib situated at the toe-end of the said insole, in a rearward direction free of the body of the said insole to which it is secured only by cementitious material, and thus the said insole is impractical in that respect.

On the other hand, in the case that a relatively less substantial box-toe than good practice dictates were incorporated in a man's or a boy's Goodyear welt shoe incorporating the said unchannelled ribbed insole (which always has been and now is the practice in shoe factories using the said unchannelled ribbed insole) then the cemented sewing rib, situated at the toe part of the insole, still would be more or less disadvantageously disturbed on the body of the insole under the influence of the straining action of the toe-wipers of the toe lasting machine thereupon, but then the disturbance of the sewing rib on the body of the insole would not be such as to render the said unchannelled ribbed insole impractical.

2

But, even then my herein disclosed invention may be advantageously adopted, as due to the aforesaid "more or less disturbance of the sewing rib situated at the toe of the insole under the strain of the toe-wipers of the toe lasting machine", the sewing rib situated at the toe-end of the insole separates entirely from the body of the insole during the initial time of wear.

It is to be appreciated that although I have herein shown permanent reinforcing sewing rib fastening means only at the toe part of the insole, it is within the scope of my invention and of this application to provide permanent reinforcing sewing rib fastening means, of any suitable form, at any additional part or parts of the said insole, other than at the back of toe forepart of the insole, as, invariably, that part of the insole is left free of such fastening means. In this broader aspect of my invention, permanent reinforcing sewing rib fastening means may be provided also at the shankpart of the insole, but such procedure, however, is not herein shown as such is not deemed necessary nor advisable, except in the case of extra heavy uppers, or of extra heavy welt shoes, such as work shoes, as the reinforcing sewing rib fabric sheet 8, in being secured by cementitious material to the underside plane face of the body of the insole enclosed by the sewing rib and in extending towards the top of the inner side face of the sewing rib and in thus eventually forming part of the welt inseam is sufficient in holding the sewing rib situated at any part of the insole, other than at the toe part, from displacement on the body of the insole at all time whenever my improved unchannelled ribbed insole for a welt shoe is incorporated in a dressy Goodyear welt shoe, such as intended for street wear.

Therefore, my invention and this application are intended to cover and do cover the provision of permanent reinforcing sewing rib fastening means also at the shankpart of the said unchannelled ribbed insole for a welt shoe whenever need be or desired, and the claims, whenever the context so permits, are to be interpreted broadly and in that sense.

My invention has for prime objective the reinforcement of that portion of the sewing rib situated at the toe part of the unchannelled ribbed insole for a welt shoe herein shown and described, to the end that the herein noted serious defective conditions at the toe lasting machine operation and during the time of wear may be eliminated and that thereby a Goodyear welt shoe incorporating my improved unchannelled ribbed insole for a welt shoe, in turn, may be improved in then embodying a box-toe more substantial than heretofore possible of embodiment in a Goodyear welt shoe incorporating the said insole, for prolonging thereby the wear of the shoe and the original

shape of the toe of the shoe, without disadvantageously affecting the smooth inner surface of the shoe insole, at least at the back of toe forepart of the insole where nearly all the pressure of the foot exists at the forepart of a shoe when in the act of walking or even of standing.

As shown in the accompanying drawings:

Figure 1 shows the underside plan view of the particular unchannelled ribbed insole for a welt shoe hereinbefore identified and the permanent reinforcing sewing rib fastening means that I have provided at the toe of the said insole;

Figure 2 shows the top plan view of the said unchannelled ribbed insole for a welt shoe and a cover that I have provided for the said permanent reinforcing sewing rib fastening means for the protection of the wearer's foot; and

Figure 3 shows a cross-section taken on line 3—3, Fig. 1, of my improved unchannelled ribbed insole for a welt shoe.

Referring further to the drawings:

I have provided the unchannelled ribbed insole for a welt shoe 1, which, preferably, is of leather, with the sewing rib 2, formed of cotton fabric, commonly known as "gem-duck," having a reinforcing core 2', which may be of any suitable material, but, preferably, of the commercially well known insole material termed "Onco," which is deemed by the applicant to be the best material for the purpose of reinforcing the sewing rib of the said insole, and an outer flange 3, and an inner flange 4, which are disposed upon and secured to the underside peripheral margin of the body of the insole 1, by the cementitious material 5, and I have provided at the toepart of the said insole permanent reinforcing sewing rib fastening means, preferably, in the form of a row of chain stitches 6, passing, preferably, through the outer flange 3, of the sewing rib, in close proximity to the sewing rib, and entirely through the body of the insole, leaving, invariably, the back of toe forepart of the insole free of such fastening means, and, as shown in Figs. 2 and 3, I have provided a cover 7, which may be in any suitable form, but which, preferably, is, as herein shown, in the form of lubricating wax worked into the stitching seam by means of a hot iron, which is intended to protect the wearer's foot from direct contact with the said stitching seam, and I have provided a reinforcing sewing rib fabric sheet 8, (such as shown in the aforesaid patent to Eno), and which forms an essential part of my invention in that both, the permanent reinforcing sewing rib fastening means, in the form of a row of stitches 6, provided by the applicant, and the said reinforcing sewing rib fabric sheet 8, form a novel combination co-operating in bringing about new beneficial results never before attained in securing the sewing rib to the body of the said insole. More specifically stated, the permanent reinforcing sewing fastening means, herein shown, preferably, in the form of a row of stitches 6, in being disposed upon the outer flange 3, of the sewing rib, hold the sewing rib from rearward movement on the body of the insole under the strain of the toe-wipers of the toe lasting machine upon the sewing rib, and the reinforcing sewing rib fabric sheet 8, in being disposed and secured to the body of the insole enclosed by the sewing rib and to the inner flange 4, of the sewing rib, co-operates with the said permanent reinforcing sewing rib fastening means in holding the sewing rib from rearward movement on the body of the insole under the strain of the toe-wipers of the toe lasting machine upon the sewing rib.

A further feature of my invention differentiating from the prior art, resides in "invariably omitting the provision of permanent reinforcing sewing rib fastening means at the back of toe forepart of the said insole" leaving the surface of that part of the insole as smooth as that of a channelled insole for a welt shoe, and then without the objectionable "gutter" common with said channelled insoles along the line of the channel due to the pressure of the foot depressing that weakened portion of the insole, and notably so when said channelled insoles are incorporated in the medium grade of Goodyear welt shoes hereinbefore identified, embodying unchannelled ribbed insole for a welt shoe as shown in Figs. 3 and 4 of the aforesaid patent to Eno, and for which medium grade of shoes my herein shown improved unchannelled ribbed insole for a welt shoe is primarily intended.

I want it well understood that it is within the scope of my invention and of this application to provide reinforcing sewing rib fastening means only around the toe-end of the insole extending to an including the corners of the toe of the insole, where maximum strength of the sewing rib is most needed due to the fact that the toe-wipers of the toe lasting machine first engage the upper, the box-toe and the sewing rib at the toe-end of the insole and force that portion of the sewing rib in a heelward direction while the toe-wipers are closing in upon the upper and the box-toe at the sides of the toe of the insole; and to the further fact that the upper and the box-toe in being made to protrude at the corners of the toe of the insole outwardly of the insole in the form of "dog ears," so-called, under the influence of the pulling over operation at the toe of the upper, makes for a most strenuous toe wiping operation at the corners of the toe of the insole subjecting the sewing rib situated at those points to excessive, undue strain.

Taking in consideration that the side of toe portions of the upper, the box-toe and the sewing rib are subjected to relatively far less degree of strain by the toe-wipers of the toe lasting machine, the absolute need of the provision of permanent reinforcing sewing rib fastening means at the sides of the toe of the insole past the corners of toe, and the provision of permanent reinforcing sewing rib fastening means, only around the toe-end of the insole extending up to and including the corners of toe of the insole, is enough to bring about the desired beneficial results in holding the sewing rib situated at the toepart of the insole from disturbance on the body of the insole at the toe lasting machine operation, except in special cases, as when the toepart of the upper and/or the box-toe are extra heavy, or in the case of extra heavy shoes, such as work-shoes. Furthermore, in providing permanent reinforcing sewing rib fastening means, such as in the form of a row of stitches disposed only around the toe-end of the insole extending up to and including the corners of toe of the insole, obviously would eliminate the need of a cover for the stitching seam at the top side plane face of the insole, and, even when the said row of stitches should extend to the side of the toe of the insole past the corners of toe of the insole, such as herein shown, a cover may be omitted, depending, on whether or not the material forming the body of the insole is of soft or firm texture; or whether or not water had been applied to the peripheral margin of the top side plane face of the firm body of the insole preparatory to the formation of the row of stitch-

es on the insole to thereby soften the surface of the firm body of the insole to allow for the sinking in of the stitches below the surface of the body of the insole; or whether or not the stitching thread is of such tensile strength as to allow for the use of a size of thread small enough to avoid undue prominence of the stitches at the top side plane face of the insole.

Suffice it to say, that my invention and this application are intended to cover and do cover the various stated forms of the invention and that the claims, whenever the context so permits, are to be broadly and accordingly interpreted to give to my invention and this application all the protection to which I am entitled under the statutes.

Having thus explained the nature of my invention and shown the same in the best form now to me known, what I claim as new and desire to secure by Letters Patent of the United States is:

1. An insole for welt shoes as herein shown and described, having, in combination, a sewing rib having an outer flange and an inner flange disposed upon and secured by cementitious material to the peripheral margin of the underside plane face of the body of the said insole; permanent reinforcing sewing rib fastening means, in the form of thread stitches disposed at the toe-part of the said insole and passing through the cemented outer flange of the sewing rib and entirely through the body of the said insole, but, invariably, leaving the back of toe forepart of the said insole free of such permanent reinforcing sewing rib fastening means; a cover disposed upon the said permanent reinforcing sewing rib fastening means situated at the top side plane face of the body of the said insole; and a reinforcing sewing rib means, in the form of a fabric sheet, disposed upon and secured by cementitious material to the underside plane face of the insole enclosed by the sewing rib, to the cemented inner flange of the sewing rib and extending towards the top of the inner side face of the sewing rib.

2. An insole for welt shoes as herein shown and described, having, in combination, a sewing rib having an outer flange and an inner flange disposed upon and secured by cementitious material to the peripheral margin of the underside plane face of the body of the said insole; permanent reinforcing sewing rib fastening means disposed at the toe-part of the said insole and passing through the cemented outer flange of the sewing rib and entirely through the body of the said insole, but, invariably, leaving the back of toe forepart of the said insole free of such permanent reinforcing sewing rib fastening means; a cover disposed upon the said permanent reinforcing sewing rib fastening means situated at the top side plane face of the body of the said insole; and a reinforcing sewing rib means, in the form of a fabric sheet, disposed upon and secured by cementitious material to the underside plane face of the said insole enclosed by the sewing rib, to the cemented inner flange of the sewing rib and extending towards the top of the inner side face of the sewing rib.

3. An insole for welt shoes substantially as herein shown and described, having, in combination, a sewing rib having an outer flange and an inner flange disposed upon and secured by cementitious material to the peripheral margin of the underside plane face of the body of the said insole; permanent reinforcing sewing rib fastening means disposed at the toe-part of the said insole and passing through a cemented flange

of the sewing rib and entirely through the body of the said insole, but, invariably, leaving the back of toe forepart of the said insole free of such permanent reinforcing sewing rib fastening means; a cover disposed upon the said permanent reinforcing sewing rib fastening means situated at the top side plane face of the body of the said insole; and a reinforcing sewing rib means, in the form of a fabric sheet, disposed

5 upon and secured by cementitious material to the underside plane face of the said insole enclosed by the sewing rib, to the cemented inner flange of the sewing rib and extending towards the top of the inner side face of the sewing rib.

10 4. An insole for welt shoes substantially as herein shown and described, having, in combination, a sewing rib having an outer flange and an inner flange disposed upon and secured by cementitious material to the peripheral margin of the underside plane face of the body of the said insole; permanent reinforcing sewing rib fastening means disposed at the toe-part of the said insole and passing through a cemented flange of the sewing rib and entirely through the body of the 15 20 25 30 35 40 45 50 55 60 65 70 said insole, but, invariably, leaving the back of toe forepart of the said insole free of such permanent reinforcing sewing rib fastening means; and a reinforcing sewing rib means, in the form of a fabric sheet, disposed upon and secured by cementitious material to the underside plane face of the said insole enclosed by the sewing rib, to the cemented inner flange of the sewing rib and extending towards the top of the inner side face of the sewing rib.

5. An insole for welt shoes substantially as herein shown and described, having, in combination, a sewing rib having an outer flange and an inner flange disposed upon and secured by cementitious material to the peripheral margin of the underside plane face of the body of the said insole; permanent reinforcing sewing rib fastening means passing through a cemented flange of the sewing rib and through the body of the said insole and disposed at any point or points within the area of the toe-part of the insole, but, invariably, leaving the back of toe forepart of the said insole free of such permanent reinforcing sewing rib fastening means; and a sewing rib reinforcing fabric sheet disposed upon and secured by cementitious material to the underside plane face of the said insole enclosed by the sewing rib, to the cemented inner flange of the sewing rib and extending towards the top of the inner side face of the sewing rib.

6. An insole for welt shoes substantially as herein shown and described, having, in combination, a sewing rib having an outer flange and an inner flange disposed upon and secured by cementitious material to the peripheral margin of the underside plane face of the body of the said insole; permanent reinforcing sewing rib fastening means passing through a cemented flange of the sewing rib and through the body of the said insole but, invariably, leaving the back of toe forepart of the said insole free of such permanent reinforcing sewing rib fastening means; and a sewing rib reinforcing fabric sheet disposed upon and secured by cementitious material to the underside plane face of the said insole enclosed by the sewing rib, to the cemented inner flange of the sewing rib and extending towards the top of the inner side face of the sewing rib.
